UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

POWER SHOVEL.

Application filed August 12, 1926. Serial No. 128,731.

This invention relates particularly to power shovels for use in confined spaces such as in mines, although not limited to this use alone.

One of the objects of the invention relates to the provision of a power shovel which requires but comparatively little space for the horizontal operation of the scoop.

Other objects of the invention reside in the provision of a power shovel which is particularly adapted for use in confined spaces such as in mines with a view toward compactness, effective operation and proper control.

15 Referring to the drawings:

Figure 1 is a top plan view of a power shovel embodying one form of my invention with parts broken away and in section;

Figure 2 is a side elevation of the machine illustrated in Figure 1 with parts broken away and in section;

Figure 3 is a partial section on the line 3-3 of Figure 2;

Figure 4 is a partial section on the line 25 4-4 of Figure 1;

Figure 5 is a partial top plan view with parts removed broken away and in section;

Figure 6 is a top plan view with parts removed and in section;

30 Figure 7 is an enlarged partial section on the line 7-7 of Figure 1; and

Figure 8 is a partial section on the line 8-8 of Figure 1.

Like numerals refer to like parts throughout the several figures.

In the drawings 1 designates a base frame which is carried on laterally spaced continuous tread devices 2 of usual construction which are adapted for the propulsion of the shovel.

40 The base frame 1 is provided with a centrally disposed concentrically bored vertical hub 3 extending upwardly therefrom. A turntable or rotatable frame 4 is carried on the base frame and is journaled on said hub 3 for angular movement in a horizontal plane with respect to the base by means of a bored hub 5 formed integrally with the turntable and extending upwardly therefrom and 45 journaled on the hub 3 of the base. See Figures 2 and 3.

50 Mounted for pivotal movement in a vertical plane at the rear of the turntable, as designated at 6, and extending forwardly

therefrom is an elevating frame 7 comprising two vertically spaced horizontal portions secured together. The lower portion of the elevating frame 7 is provided with a concentrically bored hub 8 extending upwardly therefrom and surrounding the hub 5 of the turntable, the bore of the hub 8 being sufficiently large to permit pivotal movement of the elevating frame.

55 A pair of crank arms 9 are disposed between the upper and lower portions of the elevating frame 7, and one of these crank arms is journaled on the hub 8 of the elevating frame while the other crank arm is journaled on the hub of the first mentioned crank arm. Thus are these crank arms 9 pivotally mounted coaxially on the elevating frame on a vertical axis.

60 The crank arms 9 are provided with gear segment portions 11 which mesh with respective gears 12 secured on concentric shafts 13 disposed on a vertical axis at the rear of the elevating frame 7 and journaled thereon. See Figures 1, 6 and 8. The shafts 13 extend above the upper portion of the elevating frame, and secured on the upper ends of respective shafts 13 and facing each other are two bevel gears 14. Secured on a horizontal transverse shaft 15 journaled on the elevating frame 7 above the upper portion thereof is a third bevel gear 16 meshing with both of the bevel gears 14. Thus is provided 65 means for effecting synchronous corresponding opposite angular movement of these crank arms.

70 A pair of links 17 is provided and each of these links is pivotally secured on vertical axes at respective ends thereof with the free end of a respective crank arm 9, as designated at 18, and with a forwardly facing scoop 19, as designated at 20. The links 17 are 75 provided with arms 21 at the forward or scoop ends thereof, and these arms 21 extend transversely toward each other and have their free ends pivotally and slidably engaged with each other midway between the links 17, as designated at 22.

80 As so carried the scoop 19 is vertically operable by operating the elevating frame 7 on its pivotal axis. Horizontal or radial movement of the scoop is effected by operating the crank arms 9 angularly in opposite relation by the means above described. As 85 so operated the crank arms 9 are operated

throughout a range from the positions thereof shown in Figure 1 to the positions shown in Figure 6. In this range of movement of the crank arms, the links 17 pivoting in an obvious manner carry the scoop 19 horizontally or radially and the arms 21 of the links 17, operating through the connection 22, serve to maintain the scoop in a straight path of movement. The inner position of the scoop is shown in Figures 1 and 2 and in dotted lines in Figure 6 and the outer position thereof is shown in full lines in Figure 6.

The elevating frame 7 is operated on its pivotal axis 6 for vertically operating the scoop 19 and its carrying mechanism in the following manner. The turntable 4 is provided at its forward end with a rearwardly facing rack 24, curved on the axis 6 of the elevating frame and extending upwardly from the turntable in substantially vertical disposition and between the links 17. See Figures 1, 2 and 5. Journaled on the upper portion of the elevating frame 17 immediately to the rear of the rack 24 is a transverse shaft 25 upon which is secured a gear 26 which meshes with the rack 24 for vertically operating the elevating frame with rotation of this shaft.

Power for operating the various mechanisms of the shovel is provided by an electric motor 27 mounted on the upper portion of the elevating frame 7 on the right hand side thereof. See Figures 1, 2, 3 and 5. A transverse shaft 28 is journaled on the upper portion of the elevating frame 7 adjacent the front end thereof, and mounted on this shaft is a manually controlled releasable frictional driving device 29 for driving the shaft. This driving device is operated from the motor 27 by a gear train 30 driven by a gear 31 secured on the shaft of the motor. The shaft 28 is connected to drive the shaft 25 by means of a gear train 32, so that when the driving device 29 is engaged the gear 26 is rotated from the motor 27 to roll upwardly on the rack 24 and lift the elevating frame 7.

Thus is upward movement of the crank arms 9, links 17, scoop 19 and the elevating frame 7 effected, and downward movement of the elevating frame 7 and the parts carried thereby is controlled as follows. Journaled on the upper portion of the elevating frame 7 and on the shaft 28 is a brake drum 34 provided with internal ratchet teeth 35. See Figures 1, 5 and 7. Pivotaly mounted on a spider formation 36 of the driven member of the driving device 29, which is secured to the shaft 28, is a plurality of pawls 37 which are yieldably urged into engagement with the ratchet teeth 35 of the drum 34 by springs 38 whereby to form an automatic one-way driving connection between the shaft 28 and the brake drums 34. The outer surface of the brake drum 34 is a fric-

tion surface, and a friction brake band 39, adjustable by means of a usual adjustment device 40 and fixed against rotation by engagement in a slot in the elevating frame, as designated at 41 in Figure 7, engages said outer surface of the brake drum 34 to form a friction brake therewith. The arrangement is such that the brake drum 34 is rotated with downward movement of the elevating frame 7, and related parts, whereas the upward movement of the elevating frame and related parts is effected free of this brake by reason of the pawls 37 ratcheting over the ratchet teeth 35 of the brake drum.

Another transverse shaft 43 is journaled on the upper portion of the elevating frame 7 rearwardly thereon, and this shaft is driven from the motor 27 by a gear train 44 driven by the motor gear 31. See Figures 1, 2 and 5. Mounted in this shaft 43 is a pair of manually controlled releasable frictional driving devices 45 of the planetary type, which are connected to drive another transverse shaft 46, journaled on the upper portion of the elevating frame 7 adjacent the shaft 43, by means of respective of two gear trains 47, one of which gear trains includes an additional idler gear 48 whereby the shaft 46 is driven in respective directions by the driving devices 45. A gear train 49 has respective gears thereof secured to the aforementioned shaft 15 and rotatably mounted on the shaft 46, and a manually controlled positive clutch member 50 is keyed on the shaft 46 for sliding movement thereon to engage with and disengage from a corresponding formation of the adjacent gear of the gear train 49 whereby to releasably drive the shaft 15 from the shaft 46. When the clutch member 50 is engaged the shaft 15 may be rotated in either direction by manipulation of the driving devices 45 whereby to operate the scoop horizontally in respective directions in an obvious manner.

A shaft 52 is journaled in the bore of the hub 3 of the base frame 1, the shaft being provided with an intermediate flange 53 which bears downwardly upon the upper end of the hub 3 to provide a downward thrust bearing for the shaft. See Figures 2 and 3. The shaft 52 extends upwardly from the base frame 1 and through the axial openings of the turntable and crank arms 9 and a corresponding opening in the elevating frame. A jack element 54 is axially screw-threaded downwardly into an axial bore of the shaft 52 and is accordingly raised and lowered with rotation of the shaft 52, a transverse hole 55 being provided in the upper end of the jack element in which a rod may be inserted to prevent rotation of the jack element during rotation of the shaft 52 to raise or lower the jack element. The jack element 54 is adapted for exerting

downward pressure from a roof or similar support for holding the shovel in place during operation thereof.

A downwardly facing bevel gear 56 is secured on the lower end of the shaft 52 below the base frame 1, and secured on respective of two coaxial transverse shafts 57 journaled on the base frame is a pair of bevel gears 58 which mesh with the gear 56 on opposite sides thereof for driving the shafts 57 in respective of opposite directions. See Figures 1, 2, 3 and 6. Chain and sprocket driving devices 59 serve to drive shafts 60 disposed coaxial with respective pairs of sprockets 61 of the continuous tread devices 2 from respective shafts 57 in respective opposite directions. Manually controlled positive clutch members 62 are keyed on the shafts 60 for sliding movement thereon adjacent respective sprockets 61 to engage with and disengage from respective of these sprockets for the selective driving of the continuous tread mechanisms 2. Thus by manipulation of the clutch members 62 the continuous tread devices 2 may be driven together in either direction to propel the shovel in a straight course, or driven in opposite directions for turning.

The opening in the upper portion of the elevating frame 7 through which the shaft 52 passes is relatively large and journaled in this opening and surrounding the shaft 52 is a large ring gear 63. See Figures 1, 2, 3 and 5. Keyed for sliding movement on the shaft 52 above the flange 53 is a collar 64, and a pair of alined studs 65 are secured in diametrical relation on the collar and are slidably and pivotally engaged in respective of diametrically opposite apertures in a ring 66 surrounding the collar and within the ring gear 63. A second pair of alined studs 67 are secured in diametrical relation on the ring gear 63 and are slidably and pivotally engaged in diametrically opposite apertures in the ring 66 disposed normal to the first mentioned apertures. Thus is the ring gear 63 rotatably fixed with the shaft 52 to permit vertical pivotal movement of the elevating frame 7 and with it the ring gear 63 on the axis 6 of the elevating frame.

Journalled on the upper portion of the elevating frame 7 at the left hand side thereof and extending forwardly and rearwardly is a shaft 68 and this shaft is driven from the shaft 43 by a pair of meshed bevel gears 69 secured on respective of these shafts. See Figures 1 and 5. Mounted on the shaft 68 forwardly thereon is a pair of manually controlled releasable frictional driving devices 70 of the planetary type, which are connected to drive another shaft 71, journaled on the upper portion of the elevating frame 7 in parallelism with the

shaft 68, by means of respective of two gear trains 72, one of which gear trains includes an additional idler gear 73 whereby the shaft 46 is driven in respective directions by the driving devices 70. A vertical shaft 74 is journaled on the upper portion of the elevating frame 7 adjacent the rear end of the shaft 71, and a pair of meshed bevel gears 75 secured to respective of the shafts 71 and 74 drives the shaft 74 from the shaft 71. A gear 76 secured on the shaft 74 meshes with the ring gear 63 for driving thereon. A manually controlled releasable clutch device 77 is mounted on the base frame 1 and is engageable with teeth of the bevel gear 56, as shown in Figures 1 and 2, for rotatably fixing the shaft 52 and with it the ring gear 63 with the base frame 1 for angularly operating the turntable 4 on the base frame 1 by manipulation of the driving devices 70 in an obvious manner.

Another vertical shaft 79 is journaled on the upper portion of the elevating frame 7 between the shafts 46 and 74, and a worm gear 80 is journaled on the shaft 79 and is engaged by a worm 81 secured on the left hand end of the shaft 46 for driving the worm gear therefrom. See Figures 1, 2 and 5. A manually controlled positive clutch member 82 is keyed on the shaft 46 for sliding movement thereon to engage with and disengage from a corresponding formation of the worm gear 80 whereby to releasably drive the shaft 79 from the shaft 46. A gear 83 is secured on the shaft 79 and meshes with the aforementioned gear 76 whereby to drive on the ring gear 63 through the worm gear 80 and worm 81, constituting reduction gearing, and the driving devices 70.

The clutch 50 and the clutch 82 serve for alternately operating the crank arms 9 and driving on the ring gear 63, and it will be observed that a comparatively high speed drive is provided on the ring gear 63 through the driving devices 70 for angularly operating the turntable 4 on the base frame 1, and that an additional powerful reduction gear drive on the ring gear 63 is provided for effecting proper pressure on the jack element 54 and for driving the continuous tread mechanisms 2 for propelling the shovel.

When rotating the shaft 52 for raising or lowering the jack element or for operating the continuous tread devices 2 the turntable is rotatably secured with the base frame 1 by means of a releasable locking device 84 of usual construction. See Figure 3.

The scoop 19 is provided with an ejector 85 operable longitudinally thereof for ejecting material from the scoop. This ejector is operated in the following manner. See

Figures 1 and 4. A pair of rack bars 86 are secured at their front ends to the ejector 85 and extend rearwardly therefrom, and are slidably mounted in suitable bearings 87 carried with the scoop. Mounted on the rear of the scoop is a manually controlled reversible electric motor 88, and the racks are operated by reducing gear trains 89 driven by a gear 90 secured on the shaft of this motor.

While I have shown herein and described one form of my invention, I do not wish to be limited to the precise details of construction or arrangement of parts herein shown, and described, except as specifically limited in the appended claims.

I claim as my invention:

1. In a power shovel, the combination of a frame, a scoop, a pair of crank arms pivotally mounted on said frame, means for effecting angular movement of said crank arms in corresponding opposite relation, a pair of links each of which is pivotally secured with said scoop and with a respective crank arm, and means for maintaining a predetermined path of movement of said scoop.

2. In a power shovel, the combination of a frame, a scoop, a pair of crank arms pivotally mounted on said frame for horizontal angular movement, means for effecting synchronous corresponding opposite angular movement of said crank arms, a pair of links each of which is pivotally secured at respective ends thereof with said scoop and with the free end of a respective crank arm on vertical axes, and means operating between said links for maintaining a predetermined path of movement of said scoop.

3. In a power shovel, the combination of a frame, a scoop, a pair of coaxial crank arms mounted on said frame for pivotal movement on a vertical axis, means for effecting angular movement of said crank arms in corresponding opposite relation, a pair of links each of which is pivotally secured at respective ends thereof with said scoop and the free end of a respective crank arm on vertical axes, and arms on said links at the scoop ends thereof and engaged for maintaining a predetermined path of movement of said scoop.

4. In a power shovel, the combination of a frame, a scoop, a pair of crank arms pivotally mounted on said frame, gear segments on said crank arms, a gear train operating between said segments for effecting angular movement of said crank arms in corresponding opposite relation, a pair of links each of which is pivotally secured at respective ends thereof with said scoop and with a respective crank arm, and means for maintaining a predetermined path of movement of said scoop.

5. In a power shovel, the combination of a

frame, a scoop, a pair of coaxial crank arms mounted on said frame for pivotal movement on a vertical axis, gear segments on respective crank arms, a pair of coaxial gears meshing with respective gear segments, a pair of coaxial bevel gears facing each other and secured with respective of said first mentioned pair of coaxial gears, a third bevel gear meshing with said pair of bevel gears for driving the same, a pair of links each of which is pivotally secured at respective ends thereof with said scoop and the free end of a respective crank arm, and arms on said links at the scoop ends thereof and engaged with each other for maintaining a straight path of movement of said scoop.

6. In a power shovel, the combination of a base frame, a turntable on said base frame mounted for angular movement in a horizontal plane, an elevating frame pivotally mounted on said turntable for movement in a vertical plane, a scoop, and means carried by said elevating frame and carrying said scoop for horizontal movement including a pair of correspondingly oppositely operating crank arms pivotally mounted on said elevating frame for horizontal angular movement.

7. In a power shovel, the combination of a base frame, a turntable on said base frame mounted for angular movement in a horizontal plane, an elevating frame pivotally mounted on said turntable for movement in a vertical plane, a scoop, and means carried by said elevating frame and carrying said scoop for horizontal movement including a pair of coaxial correspondingly oppositely actuated crank arms pivotally mounted on said elevating frame in substantially coaxial relation with said turntable.

8. In a power shovel, the combination of a base frame, a turntable on said base frame mounted for angular movement in a horizontal plane, an elevating frame pivotally mounted on said turntable for movement in a vertical plane, scoop carrying means including a pair of correspondingly oppositely operating crank arms pivotally mounted on said elevating frame substantially on the axis of said turntable, a revolute vertically disposed member carried independently of said elevating frame and extending through axial openings in said crank arms, a revolute ring gear surrounding said revolute member and carried by said elevating frame, and means for driving on said revolute member from said gear ring adapted to permit pivotal movement of said elevating frame.

9. In a power shovel, the combination of a base frame, a turntable on said base frame mounted for angular movement in a horizontal plane, an elevating frame pivotally mounted on said turntable for movement in

a vertical plane, scoop carrying means including a pair of correspondingly oppositely operating crank arms pivotally mounted on said elevating frame substantially on the 5 axis of said turntable, a revolute vertically disposed shaft carried by said base frame and extending through axial openings in said turntable and crank arms and a corresponding opening through said elevating 10 frame, a revolute ring gear surrounding said shaft and carried by said elevating frame, and means for driving on said shaft from said ring gear and adapted to permit said pivotal movement of said elevating 15 frame.

10. In a power shovel, the combination of a base frame, a turntable on said base frame mounted for angular movement in a horizontal plane, an elevating frame pivotally 20 mounted on said turntable for movement in a vertical plane, scoop carrying means including a pair of oppositely operating crank arms pivotally mounted on said elevating frame substantially on the axis of said turntable, and a vertical holding jack extending 25 through axial openings in said turntable and crank arms and a corresponding opening in said elevating frame.

11. In a power shovel, the combination of a base frame, a turntable on said base frame mounted for angular movement in a horizontal plane, an elevating frame pivotally mounted on said turntable for movement in a vertical plane, scoop carrying means including a pair of correspondingly oppositely operating crank arms pivotally mounted on said elevating frame substantially on the axis of said turntable, a revolute vertically disposed shaft carried with said base frame and extending upwardly through axial openings through said turntable and crank arms and a corresponding opening through said elevating frame, a revolute ring gear surrounding said shaft and carried by said elevating frame, means for driving said shaft from said ring gear and adapted to permit said pivotal movement of said elevating frame, and a jack element axially screwthreaded downwardly on said shaft.

12. In a power shovel, the combination of a base frame, propulsion means on said base frame, a turntable on said base frame mounted for angular movement in a horizontal plane, an elevating frame mounted on said turntable for pivotal movement in a vertical plane with respect thereto, a revolute member disposed coaxially with said turntable and carried independently of said elevating frame, means for driving said propulsion means from said revolute member, and means for driving said revolute member from said elevating frame adapted to permit said pivotal movement of said elevating frame.

13. In a power shovel, the combination of

a base frame, propulsion means carrying said base frame, a turntable on said base frame mounted for angular movement in a horizontal plane, an elevating frame mounted on said turntable for pivotal movement in a vertical plane with respect thereto, a revolute shaft disposed coaxially with said turntable and extending through openings in said base frame, said turntable and said elevating frame and carried on said base frame, means for driving said propulsion means from said shaft, a revolute ring gear surrounding said shaft and mounted on said elevating frame, and means for driving said shaft from said ring gear adapted to permit said pivotal movement of said elevating frame.

14. In a power shovel, the combination of a base frame, a turntable on said base frame mounted for angular movement in a horizontal plane, an elevating frame mounted on said turntable for pivotal movement in a vertical plane with respect thereto, a revolute member disposed coaxially with said turntable and carried independently of said elevating frame, a jack element axially screwthreaded on said revolute member, and means for rotating said revolute member from said elevating frame adapted to permit said pivotal movement of said elevating frame.

15. In a power shovel, the combination of a base frame, a turntable on said base frame mounted for angular movement in a horizontal plane, an elevating frame mounted on said turntable for pivotal movement in a vertical plane with respect thereto, a revolute shaft disposed coaxially with said turntable and journaled on said base frame and extending upwardly through openings in said turntable and elevating frame, a jack element axially screwthreaded downwardly on said shaft, a revolute ring gear surrounding said shaft and mounted on said elevating frame, and means for driving said shaft from said ring gear adapted to permit said pivotal movement of said elevating frame.

16. In a power shovel, the combination of a base frame, propulsion means on said base frame, a turntable on said base frame mounted for angular movement in a horizontal plane, a power operated revolute member disposed coaxially with said turntable, releasable means for driving said propulsion means from said revolute member, and a jack element associated with said revolute member for the raising and lowering of said jack element with rotation of said revolute member.

17. In a power shovel, the combination of a base frame, propulsion means on said base frame, a turntable on said base frame, mounted for angular movement in a horizontal plane, a power operated revolute

shaft carried with said base frame and disposed coaxially with said turntable and extending through an axial opening therein, releasable means for driving said propulsion means from said shaft, and a jack element axially screwthreaded on said shaft.

18. In a power shovel, the combination of a base frame, propulsion means on said base frame, a turntable on said base frame 10 mounted for angular movement in a horizontal plane, an elevating frame pivotally mounted on said turntable for movement in a vertical plane, a revolute member disposed coaxially with said turntable and carried independently of said elevating frame, releasable means for driving said propulsion means from said revolute member, a jack element associated with said revolute member for the raising and lowering of said 20 jack element with rotation of said revolute member, and means for driving said revolute member from said elevating frame adapted to permit said pivotal movement of said elevating frame.

25 19. In a power shovel, the combination of a base frame, propulsion means on said base frame, a turntable on said base frame mounted for angular movement in a horizontal plane, an elevating frame pivotally 30 mounted on said turntable for movement in a vertical plane, a revolute shaft disposed coaxially with said turntable and mounted on said base and extending upwardly therefrom through openings in said turntable 35 and elevating frame, releasable means for driving said propulsion means from said shaft, a revolute ring gear surrounding said shaft and mounted on said elevating frame, means for driving said shaft from said ring gear adapted to permit said pivotal movement of said elevating frame, and a jack element axially screwthreaded downwardly on said shaft.

40 20. In a power shovel, the combination of a base frame, a turntable on said base frame mounted for angular movement in a horizontal plane, a revolute member disposed coaxially with said turntable, releasable means for locking said revolute member with said base frame, releasable means for locking said turntable with said base frame, means carried with said turntable for driving on said revolute member, and a jack element associated with said revolute member for the raising and lowering of said jack with rotation of said revolute member.

45 21. In a power shovel, the combination of a base frame, a turntable on said base frame mounted for angular movement in a horizontal plane, an elevating frame mounted on said turntable for pivotal movement in a vertical plane with respect thereto, a

revolute shaft disposed coaxially with said turntable and carried by said base frame 65 and extending upwardly through openings in said turntable and elevating frame, a revolute ring gear surrounding said shaft and mounted on said elevating frame, means for driving said shaft from said ring gear adapted to permit said pivotal movement of said elevating frame, releasable means for locking said shaft and ring gear against rotation with respect to said base frame, means on said elevating frame including a gear meshing with said ring gear for driving on the ring gear, releasable means for locking said turntable against angular movement on said base, and a jack element axially screwthreaded downwardly 80 on said shaft.

22. In a power shovel, the combination of a base frame, a turntable on said base frame mounted for angular movement in a horizontal plane, a revolute member disposed 85 coaxially with said turntable, means for alternately locking said revolute member and said turntable with said base frame, manually controlled power operated means carried with said turntable for driving on said revolute member, scoop carrying means carried with said turntable, a second manually controlled power operated means carried with said turntable, and means for alternately operating said scoop carrying 90 means and driving on said revolute member from said second power operated means including reduction gearing for driving on said revolute member.

23. In a power shovel, the combination of a base frame, a turntable on said base frame mounted for angular movement in a horizontal plane, a revolute shaft disposed coaxially with said turntable and carried by 100 said base frame, means for alternately locking said shaft and said turntable with said base frame, a pair of power operated oppositely acting manually controlled releasable frictional driving devices for driving on said shaft in respective directions, scoop carrying means carried with said turntable, a second pair of power operated oppositely acting manually controlled releasable frictional driving devices for driving in respective directions, a releasable positive clutch 105 for operating said scoop carrying means from said second pair of driving devices, reduction gearing for driving on said shaft, and a second releasable positive clutch for driving said reduction gearing from said second pair of driving devices.

Signed at Chicago, in the county of Cook and State of Illinois, this 31st day of July, A. D. 1926.

CHARLES E. DAVIS.
